UNITED STATES PATENT OFFICE.

FREDERICK HYMANS, OF YONKERS, NEW YORK, ASSIGNOR TO OTIS ELEVATOR COMPANY, OF JERSEY CITY, NEW JERSEY, A CORPORATION OF NEW JERSEY.

ELEVATOR SAFETY APPLIANCE.

Application filed September 30, 1926. Serial No. 138,704.

The invention relates to safety appliances and particularly to safety appliances for elevators.

One feature of the invention is to provide means for operating a safety appliance in the event that a hoisting rope supporting a movable body, such as an elevator car or counterweight, stretches unduly.

Another feature of the invention lies in the provision of means for operating a safety appliance in the event of the breakage of one or more of a plurality of hoisting ropes.

Another feature of the invention lies in causing the application of a safety brake to stop the car upon failure of any one of a plurality of hoisting ropes.

Still another feature is the provision of means of the above character which is of simple construction and reliable in operation.

Other features and advantages will become apparent from the specification, taken in connection with the accompanying drawings wherein the invention is embodied in concrete form.

In the drawings:—

Figure 1 is a schematic representation of a typical elevator system illustrating the invention;

Figure 2 is a schematic view taken along line 2—2 of Figure 1 illustrating one form of safety brake that may be employed in carrying out the invention;

Figure 3 is an enlarged view taken along the line 3—3 of Figure 1 with parts broken away;

Figure 4 is a view in part section taken along line 4—4 of Figure 3;

Figure 5 is an enlarged view in part section taken along line 5—5 of Figure 3; and

Figure 6 is a view, similar to Figure 5, showing a greater number of hoisting ropes.

Referring to Figure 1, the elevator car is designated by the numeral 1 while the counterweight is designated by the numeral 2. The hoisting ropes 3 connect the car and counterweight and pass over the hoisting drum 4 at the top of the hatchway. This drum is driven by means of the hoisting motor 5 to effect the raising and lowering of the car and counterweight. 6 designates an electromagnetic brake for bringing the motor, and therefore the car and counterweight, to a stop. The guide rails for the elevator car are designated 7, while those for the counterweight are

designated 8. The bottom guide shoes for the car are designated 12. The counterweight guide shoes are designated 14. The top guide shoes for the car are omitted in order to simplify the drawing. Although, for convenience of illustration, the operating mechanism for raising and lowering the car is shown with gearing inserted between the elevator motor and the hoisting drum yet this motor may be directly connected to the hoisting drum.

A governor rope 15 extends around a tensioning sheave 16 that has a weight 17 mounted in the guides 18 at the bottom of the hatchway. From the sheave 16 the governor rope extends upwardly and has its ends secured to a hitch 20. This hitch is formed with hollow conical end portions 19 into which the ends of the governor rope extend. The rope is retained within the hitch as by cementing material positioned within the conical end portions of the hitch and surrounding the rope. The hitch is formed with spherical trunnions on its lower portion. These trunnions extend into cavities in jaw members

21 of a releasing carrier 22 carried by a bracket 75 secured to the car. The jaw members 21 are pivotally mounted on a bolt 9 extending through bracket 75 and are urged toward one another and against the trunnions by spring pressure. These jaw members act to cause the hitch to move with the car. A rope 23 is also secured to the hitch and extends downwardly therefrom. The lower portion of the rope is wound around a wedge clamp safety drum 24. The drum 24, as illustrated in Figure 2, has a screw threaded connection with oppositely threaded rods 25. These rods are non-rotatably carried by bearing supports 26 forming a part of the safety plank 27 attached to the bottom of the car.

The outer ends of the rods 25 are secured to wedge members 28 positioned between rollers 30 carried by clamping jaws 31. Clamping jaws 31 are pivotally mounted on bolts 32 secured to the safety plank 27. The clamping portion of the jaws 31 face upon, but do not engage, the guide rails 7.

Referring again to Figure 1, the governor rope extends upwardly from the hitch 20, between the jaws 42 and 44 and over the sheave 33 of a centrifugal governor 34. The governor 34 is of the flyball type wherein the ball carrying arms 35 are connected through

links 36, sleeve 37, lever 38 and link 40 to the arm 41 of jaw 42. Jaw 42 is pivotally mounted on a shaft 43 and is geared to the coacting jaw 44. Jaw 44 is pivotally mounted on a shaft 46 that is slidably carried in a guide support 47. A spring 48 surrounds a rod 49 connected to shaft 46 and urges jaw 44 toward jaw 42. These jaws are arranged to grip the governor rope upon the operation of the governor 34. A spring pressed latch 50 engages the arm 41 and prevents the jaws from gripping the governor rope until the governor 34 operates through link 40 to effect the release of this latch.

According to the preferred arrangement, the governor rope extends downwardly from the governor sheave 33 and between the jaws 51 and 52 of a rope clamp 53 carried by the car and illustrated in Figures 3 to 5. The jaws 51 and 52 of this clamp are of the same construction as the jaws 42 and 44 of the governor 34. Jaw 52 is pivotally mounted on a shaft 54. This shaft is slidably carried in guides 55 provided in ears 56 and 57 formed on a base 58. A spring 59 surrounds a rod 76 connected to shaft 54 and urges jaw 52 toward jaw 51. Jaw 51 is pivotally mounted on a shaft 60 extending through ears 56 and 57. Sleeves 61 and 62 are positioned on the shaft 60 adjacent the jaw 51 and are surrounded by a torsion spring 63. Spring 63 bears at one side against the ears 56 and 57 and, at the other side against the jaw 51. This spring tends to cause the jaws 51 and 52 to swing upwardly as viewed in Figure 1, and grip the governor rope. The upward movement of these jaws is prevented by a latch 64. Latch 64 is pivotally mounted on a pin 65 extending through lugs 66 formed on the base 58. The hooked portion of this latch extends over a lug 67 formed on the jaw 51 and retains the jaw in its lower position and away from the governor rope. Jaw 52 is also retained in its lower position, inasmuch as it is geared to jaw 51. An arm 68 is formed on the latch 64 and is provided with an aperture through which a rod 70 extends. Washers 71 are positioned on the rod 70 at opposite sides of the arm 68 and contact with the curved surfaces of the arm. Nuts 72 retain one of these washers against one side of the arm 68, while a compression spring 73 surrounding the rod 70 and bearing against the base 58 urges the remaining washer against the other side of the arm.

The base 58 is secured by bolts 74 to the bracket 75, which in turn is attached by bolts 77 to the car frame 78. The base 58 is apertured at 80 and the rod 70 extends through this aperture and is provided with a yoke 81 at its upper end. The yoke 81 pivotally connects this rod to a lever 82. Lever 82 is pinned to a pivotal shaft 83 that extends through bearing apertures in the car frame 78. A lever 84 is also pinned on shaft 83 and

extends upwardly therefrom. The upper end of the lever 84 is bifurcated and receives a collar 85 within this bifurcation. Collar 85 is pivotally connected to the bifurcated end of lever 84 by screws 86 that are threaded into the lever and have non-threaded ends extending into apertures 87 in the collar 85. This collar is loosely mounted on a shaft 88. The shaft 88 extends through and is free to turn in legs 90 of a bracket 91 connected to the car frame 78 by bolts 92. The surface of one end of the collar 85 is undulated, having projections 96 and depressions 97. This collar thus constitutes a cam and is arranged to coact with a corresponding cam 95 having projections 98 and depressions 100. Cam 95 is secured to shaft 88 by a pin 101. A compression spring 102, having washers 103 at its ends, surrounds the shaft 88 and bears at one end against a leg 90 of the bracket 91 and at the other end against the collar 85. When the rope clamp 53 is in disengaged position, the projections 96 of the collar 85 rest in the depressions 100 of the cam 95. The shaft 88 has a head 104 bearing against a washer 99 positioned at the side of a leg 90. The head 104 serves to retain the shaft within the bracket 91.

A hoisting rope equalizing bar 105 is positioned between the legs 90 of the bracket 91 and is keyed on the shaft 88. The ends of the bar 105 are provided with circular bearing apertures 106 positioned at equal distances from the shaft 88. Pins 107 extend through these apertures and connect the bar 105 to the yokes 108 of the hoisting ropes 3.

In operation the car moving up and down the hatchway acts through bracket 75 and releasing carrier 22 to cause a corresponding movement of the governor rope 15. This rope 105 passing over the sheave 33 effects rotation of the governor 34. Governor 34 is set so that, as long as the descending car does not exceed a certain speed, the governor does not operate to cause the jaws 42 and 44 to grip the governor rope. In the event that the speed of the car exceeds this certain speed, the governor operates through link 40 to overcome latch 50 and effect the release of jaws 42 and 44. These jaws, turning about their pivotal shafts, fall under the influence of gravity and grip the governor rope with a pressure determined by the force of spring 48. The motion of the governor rope is retarded causing the hitch 20 to pull out of the releasing carrier 22. The car now moves downwardly with respect to the hitch, causing the rope 23 to unwind from the wedge clamp safety drum 24 and effect the rotation of this drum. The rotation of drum 24 causes the threaded rods 25 to move longitudinally. This movement of these rods causes the rollers 30, carried by the clamping jaws 31, to ride up on the wedge members 28 and effect the gripping of the guide rail by the clamp- 130

ing jaws. This action of the clamping jaws of the wedge clamp safety brings the car quickly and smoothly to rest.

In the event of undue stretching or breaking of the hoisting cables the governor 34 does not operate to cause the application of the safety brake since the operation of this governor is dependent on the speed of the car. In such circumstances it is sometimes desirable to cause the application of the safety brake and for this purpose the rope clamp 53 is provided.

Assuming that one of a pair of hoisting ropes 3 stretches unduly or breaks, the weight of the car upon the other rope causes a swinging of the equalizing bar 105. This swinging of the bar 105 causes the shaft 88 to turn in the legs 90 of the bracket 91. As the cam 95 is secured to the shaft 88 this cam also turns. Cam 85, abutting the cam 95, cannot turn owing to its connection with the lever 84. The projections 98 on the cam 95 therefore ride out of the depressions 97 in the collar 85 and cause this collar to slide along the shaft 88 against the pressure of the spring 102. This movement of the collar 85 acting through lever 84 turns the shaft 83. Lever 82, pinned to shaft 83, is thus caused to swing upwardly, carrying the connected rod 70 upwardly also. Rod 70 acting through nuts 72 and washer 71 causes the arm 68 of the latch 64 to swing upwardly, against the force of the spring 73. Latch 64 thus releases lug 67 of the jaw 51 and permits the spring 63 to swing the jaws 51 and 52 upwardly. In the event that the car is moving downwardly these jaws grip the upwardly moving governor rope with a pressure determined by the force of the spring 59. The motion of the governor rope is retarded causing the hitch 20 to pull out of the releasing carrier 22 and effect, through the rotation of the wedge clamp safety drum, the gripping of the guide rails by the clamping jaws 31. Inasmuch as the jaws 51 and 52 are moving downwardly with the car, the rope 23 is caused to unwind rapidly from the drum 24 and effect a quick application of the clamping jaws 31 to the guide rails. Should the spring 59 possess the same strength as the spring 48 of the governor 34, the clamping jaws 31 are applied to the guide rails in one half of the time taken by the governor to cause their application. This is due to the rope clamp 53 causing the rope 23 to unwind from the drum 24 with twice the rapidity attained when the governor 34 operates. The car is thus brought quickly and smoothly to rest by the use of the rope clamp 53. In the event that the car is moving upwardly at the time one of the hoisting ropes 3 stretches unduly or breaks the safety brake is applied immediately upon the car commencing its descent.

The rope clamp may be applied to a car

irrespective of the number of its hoisting ropes. For example, Figure 6 is a view similar to Figure 5 and illustrates the application of the device where four hoisting ropes are used. In this figure the shaft 110 similar to the shaft 88 has the hoisting rope equalizing bar 111 keyed thereon. To this equalizing bar two hoisting ropes 112 are attached. A sleeve 113 surrounds a portion of the shaft 110 and has a hoisting rope equalizing bar 114 keyed thereon. To equalizing bar 114 two hoisting ropes 115 are attached. The sleeve 113 extends through the bearing in the leg 109 and has a collar 116 applied on its outer end as by screws 117 threaded in the collar and extending into slots 118 in the sleeve. The surface of the ends of the collar 116 are undulated as in the case of one end of the collar 85. Collar 116 constitutes a cam and coacts with a cam 120 and a collar 122. Cam 120 is secured to the shaft 110 by a pin 121 extending through the cam and shaft. Collar 122 fits loosely on the sleeve 113 and is connected to lever 84 in the same manner that collar 85 is connected to this lever. A spring 123 similar to the spring 102 surrounds the sleeve 113 and, acting through washers 119, bears at one end against the leg 109 and at the other end against the collar 122.

In the event that one of the hoisting ropes 112 stretches unduly or breaks thus causing the shaft 110 to be turned, the cam 120 turns with respect to the collar 116. Collar 116 is prevented from turning owing to its splined connection with the sleeve 113 which is held stationary by the hoisting ropes 115 acting through equalizing bar 114. The turning of cam 120 causes collar 116 to slide along the sleeve 113, the screws 117 sliding in the slots 118. Collar 122 also moves along the sleeve 113 against the pressure of the spring 123 owing to the movement of the adjacent collar 116. Movement of collar 122 is transmitted to lever 84 as in the case of the collar 85 and effects the operation of the wedge clamp safety to cause the stopping of the car.

In the event that one of the hoisting ropes 115 stretches unduly or breaks, thus causing the sleeve 113 to be turned, the collar 116 is caused to turn with respect to cam 120 and collar 122. Cam 120 remains stationary owing to its shaft 110 being held stationary by the hoisting ropes 112 acting through the equalizing bar 111. The turning of collar 116 with respect to the cam 120 causes this collar to slide along the sleeve 113. Adjoining collar 122 is thus moved along the sleeve 113 effecting the movement of the lever 84 and the operation of the wedge clamp safety to stop the car as before.

After the rope clamp has operated to grip the governor rope and apply the safety, it may be released by forcing the jaws 51 and 52 downward manually. The latch 64 may then be snapped over the lug 67 of the jaw

51 and the device is ready for another operation. The safety is reset by rewinding the rope 23 upon the drum 24 by hand. The hitch 20 is then replaced in the releasing carrier 22 carried by the car.

It is to be understood that this invention may be used with any form of safety brake. It may also be applied to the counterweight as well as to the car.

10 As many changes could be made in the above construction and many apparently widely different embodiments of this invention could be made without departing from the scope thereof, it is intended that all matter contained in the above description or 15 shown in the accompanying drawings shall be interpreted as illustrative and not in a limiting sense.

What is claimed is:

20 1. In an elevator system, a movable body in the hatchway, hoisting ropes for said movable body, a safety appliance for said movable body, roping connected with said safety appliance, means adapted upon operation to 25 grip said roping to cause the operation of said safety appliance to stop said body, means actuated upon the breaking of a hoisting rope to cause the operation of said gripping means, additional means adapted upon operation to 30 grip said roping to cause the operation of said safety appliance to stop said body, and means actuated upon the speed of said movable body exceeding a predetermined value to cause the operation of said additional 35 gripping means.

2. In an elevator system, a movable body in the hatchway, hoisting ropes supporting

said movable body, a safety appliance carried by said movable body, roping connected with said safety appliance, and means for gripping said roping, said gripping means being arranged to be actuated by one hoisting rope upon the breaking of another hoisting rope to effect the operation of the safety appliance to cause the stopping of the body. 40

3. Means for causing the operation of a governor rope actuated safety appliance comprising, coacting jaws carried by the car, spring means tending to cause said jaws to grip the governor rope, a latch for retaining said jaws away from the governor rope, and means controlled by the hoisting ropes for releasing said latch to cause the jaws to grip the governor rope and effect the operation of the safety appliance. 45

4. In an elevator system, a movable body in the hatchway, hoisting ropes supporting said movable body, a safety brake on said movable body, a governor rope connected to the movable body, a speed governor, driven 60 by said governor rope and adapted to grip said governor rope when the speed of the movable body exceeds a predetermined value, to cause the operation of the safety brake to effect the stopping of the movable body, and gripping means cooperating with the hoisting ropes and adapted to grip the governor rope upon the failure of a hoisting rope and cause the operation of the safety brake to effect the stopping of the movable body. 65

In testimony whereof, I have signed my name to this specification.

FREDERICK HYMANS.
